UNITED STATES PATENT OFFICE

99,797

DESIGN FOR A DIRECTIONAL SIGNAL CASING

John Ralph Haines, Medford, N. J.

Application February 8, 1936, Serial No. 61,048

Term of patent 14 years

To all whom it may concern:

Be it known that John Ralph Haines, a citizen of the United States, residing at Medford, county of Burlington, and State of New Jersey, has invented a new, original, and ornamental Design for a Directional Signal Casing, of which the following is a specification, reference being had to the accompanying drawing, forming a part thereof.

Figure 1 is a view in front elevation of the directional signal casing showing my new design.
Figure 2 is a plan view of the same.

Figure 3 is an end view.

What is claimed is:

The ornamental design for a directional signal casing, as shown.

JOHN RALPH HAINES.
